CONTROL FOR ELECTRICAL APPLIANCES OR SIMILAR ARTICLE

Eugene R. Russell, Chicago, Ill., assignor to McGraw-
Edison Company, Elgin, Ill., a corporation of Dela-
ware

Application February 6, 1959, Serial No. 54,486

Term of patent 14 years

(Cl. D26—13)

Fig 1 is a top perspective view of a control for electrical appliances or similar article, showing my new design;

Fig. 2 is a top plan view;

Fig. 3 is a side elevational view;

Fig. 4 is an end elevational view; and

Fig. 5 is a bottom perspective view thereof.

The dominant features of my new design are shown in solid lines in the drawing, broken line showings of legible matter and an electric connecting cord being for illustrative purposes only.

I claim the ornamental design for a control for electrical appliances or similar article, substantially as shown and described.
